UNITED STATES PATENT OFFICE

EDGAR MAYNARD CAMP, OF DETROIT, MICHIGAN, ASSIGNOR TO RECORDING CHANGE MACHINES INC., OF DETROIT, MICHIGAN, A CORPORATION OF MICHIGAN

AUTOMATIC CHANGE-MAKING MACHINE

Application filed September 10, 1927. Serial No. 218,787.

This invention relates to automatic change making machines and the object of the invention is to provide an automatic change making machine of the selective type in which a key representing the amount of a given sale is first operated. Following this operation a key or lever representing the amount tendered by the customer is actuated and the machine, by means of a selection system, makes the subtraction automatically and automatically ejects the proper change in coins for any given transaction.

Another object of the invention is to provide a keyboard carrying the keys representing sales amounts from 1 cent to 99 cents and so arranged in rows laterally and longitudinally that any key in any row performs a function common to all of the keys in that particular lateral or longitudinal row.

These objects and the several novel features of the invention are hereinafter more fully described and claimed and the preferred form of construction by which these objects are attained is shown in the accompanying drawings in which—

Figs. 1 and 1A are diagrammatic views of a chart on which the fundamental principles underlying the operation of the machine are based.

Fig. 2 is a plan view of the keyboard of the machine and operating levers.

Fig. 3 is a diagrammatic view showing the relationship between the keyboard and the silver selector slides and including a chart on which the operation and construction of the silver selector slides are based.

Fig. 4 is an elevation of the front of the machine.

Fig. 5 is an elevation of the right end of the machine.

Fig. 6 is a section taken on line 6—6 of Fig. 4.

Fig. 7 is a detail showing the mounting for the selector slides and compensating mechanism for the parallel penny bars.

Fig. 8 is a plan view partially in section of the penny selector slides mounted on a bracket supported from the right hand side frame of the machine.

Fig. 9 is an elevation thereof.

Fig. 10 shows the relative position of the lower ends of the key stems and parallel penny bars operated thereby and the nickel and silver selector slides and release slide.

Fig. 11 is a plan view of the mechanism with which the lower lugs of the nickel selector slides co-act.

Fig. 12 is an elevation of the three nickel selector slides showing the relative position of the release lever studs therewith.

Fig. 13 is a section showing the lock and release mechanism for the operating levers.

Fig. 14 is a perspective view of one of the primary selector shutters.

Fig. 15 is a perspective view of one of the secondary selector shutters.

Fig. 16 is a section showing one of the operating levers and the enabling mechanism from which the nickel ejecting mechanism may be operated.

Fig. 17 shows the relative position of the secondary selector shutters in relation to the silver selector slides.

Fig. 18 is an enlarged view of a portion of the nickel selector system taken from the right hand of Fig. 11.

Fig. 19 is a side elevation of one of the enabling levers for the silver selection system.

Fig. 20 is an elevation of the 11 selector slides for the silver selection system.

Fig. 21 is a perspective view of the relative position of the key stems with one of the primary selector shutters.

Fig. 22 is a section taken on line 22—22 of Fig. 5 showing the ejection mechanism for the penny system.

Fig. 23 is an elevation of the operating lever release slide.

Fig. 24 is a section similar to Fig. 16 showing a portion of the enabling mechanism for the silver selection system.

The operation of the machine is based on the chart shown in Figs. 1 and 1A. The horizontal columns on the chart represent the amounts receivable, amounts due, and the change to be returned in pennies, nickels, dimes, quarters and half dollars. Amounts due represent the amount of the sale and the amounts receivable for the particular amounts due are listed in the amounts re-

ceivable row directly above the amounts due row. This machine contemplates the return of change in coins for any sale from 1 cent to 99 cents. As shown in Fig. 2 the sale keys are numbered to represent the sales from 1 cent to 99 cents and are arranged in twenty longitudinal rows corresponding to the twenty vertical rows on the chart and in five lateral rows corresponding to the five horizontal rows on the chart. The sale keys are numbered consecutively starting at the bottom right hand end of the keyboard and numbering upwardly in each row consecutively and toward the left hand end of the keyboard. The amounts receivable for these sales are represented by the five keys at the bottom of Fig. 2 numbered 100, 50, 25—75, 10 and 5. The chart is laid out with the same arrangement as the sales key keyboard shown in Fig. 2. That is, in the first square at the bottom right hand end of the chart the sales amount or amount due is 1 cent, in the square above the amount due is 2 cents, then 3 cents, 4 cents and 5 cents. In the second vertical row the amount due is 6 cents and this row is numbered consecutively in vertical order to 10 cents so that the squares on the chart outlined in heavy black lines are in the same position as the keys on the keyboard. When the amount due is 1 cent as indicated in the square at the lower right hand corner of the chart in Fig. 1 and the amount tendered is 1 dollar in the amounts receivable row, by reading downwardly in the vertical column marked 100 it will be seen that the change to be returned to the customer consists of 4 pennies, 2 dimes, 1 quarter and 1 half dollar, making a total of 99 cents returned from 1 dollar for a 1 cent purchase. Similarly if the amount received is 50 cents for a 1 cent purchase the change to be returned consists of 4 pennies, 2 dimes and 1 quarter. If 25 cents is the amount received the change paid out by the machine should consist of 4 pennies and 2 dimes. In the next vertical column reading downwardly if the amount received is 10 cents for a 1 cent purchase the machine must return 4 pennies and 1 nickel. In the next column if the amount received is 5 cents the machine must return 4 pennies.

In the next square to the left the amount due is 6 cents and if the amount received is 1 dollar the change to be returned by the machine consists of 4 pennies, 1 nickel, 1 dime, 1 quarter and 1 half dollar. If the amount received is 50 cents the change to be returned consists of 4 pennies, 1 nickel, 1 dime and 1 quarter. If the amount received is 25 cents the coins returned should be 4 pennies, 1 nickel and 1 dime. If 10 cents is received on a 6 cent purchase the amount returned should be 4 pennies. It will be noted that for any amount receivable for a 1 cent or 6 cent purchase it is necessary to return 4 pennies. This

is also true for an 11 cent, 16, 21, 26, and 31 cent purchase and so on in the lower horizontal row across the chart. In the second horizontal row across the chart it is necessary to return 3 pennies on any sale made in that row in which the sale or amount due is 2, 7, 12, 17 cents and so on. In the third row it is necessary to return 2 pennies for each sale. In the fourth horizontal row it is necessary to return 1 penny on each sale. In the top row the amounts due end in 5 and 0 and no pennies are returned on any sale in the top horizontal row. It will thus be seen that upon depressing any key in the lower row of sale keys shown in Fig. 2 it is necessary to return 4 pennies. Upon depressing any key in the second lateral or horizontal row of sale keys it is necessary to return 3 pennies. Upon depressing any key in the third lateral or horizontal row of sale keys it is necessary to return 2 pennies and upon depressing any key in the fourth lateral row it is necessary to return 1 penny. For this purpose four bars are provided as shown in Fig. 5 numbered 1, 2, 3 and 4. The upper edges of these bars are turned over as shown to provide a flat face on which the lower ends of the sale key stems rest. The bar 4 extends beneath the first lower lateral row of key stems while the bars 3, 2 and 1 extend beneath the key stems in the succeeding lateral rows of keys. As shown in Figs. 4 and 7 a bell crank 5 is provided at each end of each of the four bars and each bell crank is pivotally mounted in a bracket 6 secured to the adjacent side frame of the machine. One end of each bell crank 5 is pivotally secured to the adjacent end of the respective bar while the vertical arm is pivotally secured to an equalizing bar 7 extending in parallel relation with the respective bars 1, 2, 3 and 4. By this arrangement downward pressure applied to any point on any of the bars numbered 1, 2, 3 and 4 causes the bar to move downwardly uniformly as the bell cranks 5 maintain the bars 4 and 7 in parallel relation horizontally at all times. As shown in Figs. 4, 5, 8 and 9 four bell cranks are provided numbered 8, 9, 10 and 11. The turned over upper edge of the bars 1, 2, 3 and 4 engage over the ends of the respective bell cranks 11, 10, 9 and 8 so that downward movement of any bar produces a counter clockwise movement of the respective bell crank 11, 10, 9 or 8 on its pivot as will be understood from Fig. 9. A bracket 12 is secured to the right hand side frame of the machine and is provided with depending ears 13 shown in Fig. 9 on which the bell cranks 8, 9, 10 and 11 are pivotally mounted. A pair of guide brackets 14 are secured to the bracket 12 and three slides 15, 16 and 17 are slidably mounted in the brackets 14. These slides are drawn to the right of Figs. 8 and 9 by the springs 18 which are attached to the slides and are secured to an arm 19 which is fas-

tened to the bracket 12. Each slide is provided with a depending end 20 shown in Fig. 9 adapted to engage the bracket 14 and limit movement of the slide to the right of Fig. 9 under action by the springs 18. The bell crank 8 is provided with a stud 21 in the upper end thereof riding in slots provided therefor in the slides 16 and 17 so that counter clockwise movement of the bell crank 8 moves the slides 16 and 17 to the left of Fig. 8. The slide 17 is provided with an upwardly extending cam 22 and the slide 16 is provided with an upwardly extending cam 23 while the slide 15 is provided with an upwardly extending cam 24. By movement of the slides 16 and 17 to the left of Fig. 8 the cams 22 and 23 are moved to the left of Fig. 8. As shown in Fig. 22 the cam 22 is adapted to pass beneath a pawl 25 which is pivotally mounted in an arm 26 secured to the shaft 27. An ejector arm 28 is pivotally mounted on the shaft 27 and is provided with an extending end 29 and the pawl 25 is normally held out of engagement with the end 29 by the spring 30. Upon movement of the slide 17 and cam 22 by the stud 21 on the bell crank 8, the cam 22 is moved under the pawl 25 and raises the pawl upwardly on its pivot so that the end of the pawl engages over the end 29 of the arm 28. Upon subsequent rotation of the shaft 27 and arm 26 secured thereto the pawl 25 engaging the end 29 turns the ejector arm 28 with the shaft 27. The ejector pawl on the upper end of the arm 28 is provided with a deeper notch than the other ejector pawls and is adapted to eject two pennies from the stack immediately thereover. The cam 23, as shown in Figs. 5 and 9, is adapted to engage beneath a pawl 31 shown in Fig. 5 which is pivotally mounted on an arm 32 attached to the shaft 27 and the cam 23 is adapted to move the pawl 31 into engagement with the end of the arm 33. This construction is the same as that shown in Fig. 22 and the arm 33 is adapted to eject 2 pennies from the coin stack positioned directly thereover. The cam 24 shown in Figs. 5, 8 and 9 is formed integrally with the slide 15 and upon movement to the left engages beneath the pawl 34 pivotally mounted on an arm 35 secured to the shaft 27 and the end of the pawl is adapted to be engaged over the lower end of the arm 36 which is pivotally mounted on the shaft 27. This arm 36 is adapted upon movement to eject 1 penny from a coin stack which is preferably positioned directly thereover. Referring to Fig. 8 it will be noted that the stud 21 upon downward movement of the bar 4 moves the two slides 16 and 17 to the left producing movement of the cams 22 and 23 and engaging the pawls 25 and 31 over the lower ends of the ejector arms 28 and 33 which upon subsequent turning of the shaft 27 are adapted to eject 2 pennies from each coin stack thereabove making a total of 4 cents. By this arrangement the operation of any key in the lower lateral row across the keyboard sets up enabling mechanism to eject 4 pennies but the actual ejection or movement of the ejector levers does not take place until the shaft 27 is turned by a mechanism hereinafter described. The stud 37 shown in Fig. 8 extends through slots in all three slides but only engages slides 15 and 17. Upon movement of this stud to the left, produced by downward movement of the bar 3, the slides 15 and 17 are moved to the left producing a corresponding movement of the cams 22 and 24 which moves the enabling pawls 25 and 34 over the lower ends of the ejector arms 28 and 36 so that upon subsequent rotation of the shaft 27 in a counterclockwise direction in Fig. 22 the arm 28 ejects 2 pennies from its coin stack while the arm 36 ejects one penny from its coin stack making a total of 3 cents returned upon depression of any key in the second lower lateral row on the keyboard. Upon depression of any key in the third lateral row it is necessary to return two cents to the customer and any key in this row will depress the bar 2 to move the stud 38 to the left of Fig. 8. This stud engages only the slide 16 which moves the cam 23 to the left thus moving the enabling pawl 31 over the lower end of the ejector arm 33 so that subsequent turning of the shaft 27 turns the arm 33 to eject 2 pennies from the coin stack thereabove. The bell crank 11 is provided with a stud 39 which engages the slide 15 upon depression of the bar 1 and moves the slide 15 and cam 24 to the left of Fig. 8. This positions the enabling pawl 34 over the lower end of the arm 36 so that when the shaft 27 is turned in a counterclockwise direction 1 penny is ejected from the coin stack with which this arm is operative. In this manner the first operation upon the depression of any sale key is to enable the machine when operated to return the correct number of pennies. As shown in the upper portion of Fig. 4 each key stem is provided with a lug 40 and a spring pressed shutter 41 is pivoted at 42 in the machine frame so that when any key stem is pushed downwardly the shutter 41 engages behind the lug 40 to hold the key stem in the depressed position against its return spring 147 until the shutter 41 is released.

Three separate selection systems are incorporated in the machine, the first being the penny system just described, the second being the nickel system and the third being the silver system which takes care of the dimes, quarters and half dollars. The penny system as hereinbefore described, and as shown in Fig. 10, is operated by the lower ends of the key stems. The nickel and silver systems are operated from the shoulders 43 on the key stems shown in Fig. 10. For this purpose a primary selector shutter 44, shown in Figs. 7, 14 and 21, is provided for each vertical or

longitudinal row of five keys on the sales key board. Each shutter 44 is provided with a flange having five notches 45 for one vertical or longitudinal row of five key stems as shown in Figs. 14 and 21. The shoulders 43 of the key stems engage over the flange of the primary selector shutter 44 and these selector shutters are pivotally mounted at 46 shown in Figs. 4 and 7 to frame members of the machine and are each provided with a longitudinal bail 47 supported in the lower ends of the shutter arms 48 which are formed integrally with the respective shutter. Upon downward movement of any key stem as will be understood from Fig. 7, the respective primary selector shutter 44 is turned in a clockwise direction on its pivot 46, the action being similar to the action of a bell crank. As will be understood from Fig. 4 twenty selector shutters are pivotally mounted in the machine corresponding to the twenty vertical or longitudinal rows of keys in the sales keyboard shown in Figs. 2 and 4. By this arrangement when any key in any one of the twenty longitudinal rows is depressed the primary selector shutter for that row of keys will be turned on its pivot 46 to a corresponding degree.

Fourteen selector slides are provided, three of which are for the nickel system and eleven of which are for the silver system. These slides extend across the machine transversely at right angles to the different primary selector shutters and the different slides are provided with lugs adapted to be engaged by the bails 47 of the primary selector shutters as will be understood from Figs. 4 and 7. The three selector slides for the nickel system are shown in Fig. 12 and are numbered 49, 50 and 51. The relative position of these slides to the slides of the silver system is shown in Figs. 10 and 5. As shown in Figs. 4 and 7 these selector slides for both the nickel and silver systems rest on the brackets 6 secured to the side frames of the machine to hold the selector slides in an upright position. A spring 53 shown in Figs. 12 and 20 is secured to each slide and to an adjacent portion of the machine tending to draw the respective selector slides to the right and holding the lugs on the upper edges thereof in engagement with the bails 47 of the respective primary selector shutters. By this arrangement the depression of any sale key will turn the respective primary selector shutter on its pivot so that the bail 47 of that shutter will move any slide to the left having a lug on the upper edge engaging the bail of that shutter.

As shown in Fig. 11 five studs are provided numbered 54, 55, 56, 57 and 58. A cross frame member 59 is provided shown in Figs. 11 and 18 which connects the two side frames of the machine. A bracket 60 is secured to the frame member 59 as shown in Fig. 11 and is provided with five extending lugs sup-

porting the pivot pins 61 for the pivoted members 62. The studs 54, 55, 56, 57 and 58 are secured to the pivoted members 62 as shown in Fig. 18 and each member 62 is provided with a stop 63 preventing downward movement of the member 62 and respective stud. Each member 62, as shown in Figs. 11 and 18, is provided with a depending arm 64 carrying a pin 65 in the lower end thereof. This pin 65 engages in a notch 66 in a latch 67 which is pivotally mounted at 68 shown in Fig. 11 on each respective operating lever 69, 70, 71, 72 and 73. The back of the notch 66 is cut on a radius whose axis is the center of the shaft 74 on which the respective operating lever turns. By downward movement of the lever 73 shown in Fig. 18 the latch 67 is moved downwardly therewith and the pin 65 which, with the arm 62 remains stationary at this time, rides in the notch 66 of the latch 67 and prevents the end of the latch 67 from engaging the companion arm 75. The levers 69, 70, 71, 72 and 73 are all rotatable on the main operating shaft 74 during the first or primary downward movement thereof as will be understood from Figs. 2, 16 and 24, until the extending ends thereof engage the bail 130 at which time the shaft 74 is rotated by the operating lever engaging the bail and by means of the gears 131 and 132 shown in Fig. 6 the shaft 91 is rotated to operate the mechanism for ejecting the coins from the coin stacks. Thus there are two functions embodied in one continuous downward movement of any operating lever, the first or primary movement setting the enabling mechanism for ejecting the selected coins and the secondary movement rotating the shafts 74 and 91 and actually ejecting the coins. A diagrammatic view of the nickel selector slides and the studs 54, 55, 56 and 57 and 58 in relation thereto is shown in Fig. 12. It will be noted from this figure that the slide 49 has three lugs 76 on the bottom edge thereof normally resting on the three studs 54, 55 and 56. The selector slide 50 has one lug 77 on the bottom resting on the stud 56 and the selector slide 51 is provided with a lug 78 resting on the stud 58. As hereinbefore explained the selector slides are adapted to be moved to the left by the bails 47 of the primary selector shutters. When any of these slides are moved to the left the respective lug is moved off from the companion stud and the spring 79 shown in Fig. 18 draws the latch 67 to the right and as this latch 67 is in engagement with the pin 65 the member 62 which is in the form of a bell crank is turned in a counterclockwise direction until the latch 67 engages the end of the companion arm 75. This positions the end of the latch 67 in engagement with the companion arm 75 so that if the lever 73 is pressed downward at this time the latch 67 and arm 75 are carried downwardly therewith.

There are five arms 75 co-acting with the five latches 67 on the five operating levers 69, 70, 71, 72 and 73 and these arms are mounted on the brace rods 102 shown in Figs. 6 and 16 which are supported in the members 80 and 143. The members 80 and 143 are rotatable on the main operating shaft 74 and together with the rods 102 form a frame-work adapted to be swung against the tension of the spring 123 on the shaft 74. This frame-work may be swung by downward movement of any latch 67 when it engages with its companion arm 75 as will be understood from Fig. 18. The member 80 carries a stud 81 riding on the end 82 of a cam lever 83 which is rotatable on the fixed shaft 84. This lever 83 at the opposite end is provided with a toggle joint connecting it with the shaft 85 which is the enabling shaft for setting the nickel release mechanism. This shaft 85, as shown in Fig. 6, is provided with an arm 86 having a flattened lug 87 shown in Figs. 5 and 6. When the member 80 is turned on the shaft 74 the stud 81 turns the cam lever 83 on its pivot and by means of the toggle joint shown in Fig. 16 the shaft 85 is turned in a counter clockwise direction. By this arrangement the arm 86 on the end of the shaft having the flattened lug 87 shown in Figs. 5 and 22 is moved downwardly allowing the spring 88, shown in Fig. 22, to engage the enabling pawl 89 over the end of the lever 90 which is rotatable on the shaft 91. The arm 92 on which the pawl 89 is pivoted is secured to the shaft 91 while the rotatable lever 90 is provided with an upper end 93 which is connected by means of a toggle joint to the lever 94 which is rotatably mounted on the stationary portion of the shaft 27. By this arrangement clockwise rotation of the shaft 91 and lever end 93 turns the lever 94 in a counter clockwise direction and this lever has a notched upper end for pushing a nickel out of the coin stack immediately thereabove. A chute is preferably provided for delivering the coins to the customer after they have been ejected from the stacks.

Referring to the chart at the right end of Fig. 1, in the vertical column in which the amounts due are from 1 to 5 cents, it will be noted that when 10 cents is the amount received for any amount in this vertical column it is necessary to return a nickel. For this reason a lug 96 is provided on the top of the selector slide 50 shown in Fig. 12 and this lug 96 is in engagement with the bail 47 of the primary selector shutter which is operated by the first vertical row of keys shown at the right hand end of Fig. 2. The position of this bail is indicated by the dotted lines in Fig. 12 bearing the numbers 1-5. It will thus be seen that the depression of any key in the first vertical or longitudinal row will move the slide 50 to the left of Fig. 12 allowing the stud 57 to raise under action by the spring

79 shown in Fig. 18 so that when the 10 cent amount receivable key at the bottom of Fig. 2 is depressed a nickel is ejected from the nickel stack by the mechanism hereinbefore described. In the next vertical column on the keyboard in which the amounts due are from 6 to 10 cents and as will be understood from the chart it is necessary to return a nickel when the amount received is a quarter, half dollar or a dollar. For this reason the lug 97 is provided on the top of the selector slide 49 and lies in contact with the bail of the primary selector shutter for the second longitudinal row of keys shown in Fig. 2 and numbered from 6 to 10. In Fig. 12 the position of this bail is indicated by the dotted lines numbered 6-10. When this slide 49 is moved to the left by movement of the said bail the lugs 76 on the bottom of the slide 49 are moved off from the studs 54, 55 and 56 allowing these studs to rise as will be understood from Fig. 18 so that a subsequent depression of the quarter, half dollar or dollar amount received keys at the bottom of Fig. 2 will eject a nickel from the coin stack. The dime key for amounts receivable shown in Fig. 2 is depressed when the amount received is the multiple of ten with the exception of the half dollar and dollar amounts. Thus if the amount received is 10, 20, 30, 40, 60, 70, 80 or 90 cents the dime key marked 10 at the bottom of Fig. 2 is depressed. The nickel key for amounts receivable is depressed for all amounts receivable ending in five with the exception of the 25-75 key. This nickel key numbered 5 is used when the amount received is 5, 15, 25, 45, 55, 65, 85, 95 and 1.05 cents. \$1.05 is receivable for a sale of 96 to 99 cents in the last column on the keyboard and would consist of a half dollar, a quarter and 3 dimes or 3 quarters and 3 dimes. For this reason the bail for this last vertical row of keys for sales amounts or amounts due from 96 to 99 cents engages the lug 98 on the selector slide 51 moving this selector slide to the left and allowing the stud 58 to raise so that when the nickel amount received key is depressed a nickel is returned, the remaining change being of course taken care of in the penny system. Referring to the chart in the fifth vertical column from the right end of Fig. 1 it will be noted that when the amount of the sale or amount due is 21 to 25 cents and the amount received is 30 cents it is necessary to return a nickel when any one of these five keys is operated. For this purpose the bail of the primary selector shutter for this longitudinal row of keys contacts the lug 99 on the slide 50 shown in Fig. 12 and moves the lug 77 on the bottom of this slide off the stud 57 allowing this stud to raise as will be understood from Fig. 18 so that subsequent depression of the amount received key marked 10 at the bottom of Fig. 2, which takes care of the 30 cents received, will eject a nickel

from the coin stack. When the amount of the sale is from 26 to 30 cents, as shown in the sixth vertical column from the right end of Fig. 1, and the amount received is 35 cents it is necessary to return a nickel. The bail 5 operated by any key in this row engages the lug 101 on the slide 51 and moves this slide to the left of Fig. 12 so that the lug 78 on the bottom moves off from the stud 58 so that 10 subsequent depression of the amount received key bearing the number 5 at the bottom of Fig. 2 will eject a nickel from the coin stack.

The bails 47 of the primary selector shutters which extend across the three nickel selector slides shown in Fig. 12 also extend across the upper edges of the eleven silver selector slides shown in Fig. 20 and these eleven selector slides are provided with lugs as shown on the upper edges engaging the bails 47 of the primary selector shutters. Referring to the chart in Fig. 3, this chart is an exact index for the number of selector slides required in the silver system and the arrangement of upper and lower lugs thereon. A selector slide is required for each vertical row of "sale" keys whose tabulations on the said chart differ. The chart shows eleven such differences hence eleven selector slides are necessary. The longitudinal bails 47 on the primary selector shutters 44 contact the upper lugs on the selector slides and operate them thereby. The lower lugs on the selector slides contact the secondary selector shutters, (mounted in brackets on the 69, 70 and 71 operating levers) and operate the secondary selector shutters 104 thereby. Each key in any given longitudinal row of five keys will thus operate the same selector slide or slides. Hence, and as will be understood from said chart, selector slides numbered 1, 4, 7 and 10 require one upper lug only while two are necessary for selector slides numbered 2, 3, 5, 6, 8, 9 and 11. A further illustration of the number and location of both upper and lower 45 lugs on the selector slides is disclosed on the diagram at the bottom of Fig. 3 wherein the tabulations on the chart are graphically positioned and designated. In this diagram the contact points between the bails 47 of the primary selector shutters and the lugs of the silver selector slides are indicated by black squares on the selector slides. The position of the bails 47 of the primary selector shutters is indicated by the vertical dotted lines 50 and the key numbers operating these bails are indicated in each line. It will be noted that twenty bails are provided corresponding to the twenty longitudinal rows of keys but only the first eighteen actuate the silver selector 55 slides as no silver is returned in taking more than 90 cents from a dollar. As will be readily understood from Fig. 7 depression of any key stem by means of the shoulder 43 thereon turns the respective primary selector shutter on its axis 46 so that the bail 47 of that se-

lector shutter engages the companion lug on the respective selector slide and moves the selected selector slide to the left against the tension of a spring 53 shown in Fig. 20 which is attached to a convenient portion of the machine frame. The silver system is controlled by the three amount received keys marked 1 dollar, 50 and 25-75 in conjunction with the eleven silver selector slides shown in Figs. 3 and 20. These keys are attached to the three operating levers 69, 70 and 71 as shown in Fig. 4 and a bracket 103 is attached to each of these levers as will be understood from Figs. 4, 16 and 17. Four secondary selector shutters 104, shown in Figs. 4, 15, 16 and 17 are pivotally mounted in the arms of the bracket 103 which is secured to the operating lever 69. Three secondary selector shutters 104 are pivotally mounted in the bracket 103 on the operating lever 70 and two secondary selector shutters 104 are pivotally mounted in the bracket 103 on the operating lever 71. The upper edges of these selector shutters, as will be understood from Figs. 15 and 17, engage the lugs on the bottom of the silver selector slides shown in Fig. 20. As will be noted from Fig. 20 there are nine different rows of lugs on the bottom edges of the eleven selector slides which co-act with the upper edges of the nine secondary selector shutters 104 which are preferably spring urged into engagement with their respective lugs. Cooperative with these nine secondary selector shutters are nine enabling levers 105, 106, 107, 108, 109, 110, 111, 112, and 113. These enabling levers as shown in Fig. 6 are rotatably mounted on the main shaft 74 and are each provided with a stud 114 shown in Fig. 19 at the lower end riding on the curved end of a bell crank 115 which is rotatable on the stationary shaft 84. Each enabling lever is provided with a notched lug or end 116 having a V notch therein as will be understood from Fig. 17 and the secondary selector shutters are each provided with a lug or end 117 shown in Fig. 15 adapted to be moved into alignment with the notch 116 of the respective enabling lever. The secondary selector shutters normally are in position shown in Fig. 17 so that upon continued depression of any of the levers 69, 70 or 71 the secondary selector shutters are carried down with these levers and pass inoperatively between their companion enabling levers. The purpose of any silver selector slide is to turn certain of these secondary selector shutters on their pivots so that the lugs or ends 117 thereon engage in the notched lug or ends 116 on the enabling levers. When this has occurred the depression of the respective amount received levers 69, 70 or 71 turns these selected enabling levers in a counter clockwise direction on the shaft 74, as will be understood from Fig. 4. As will be understood from Fig. 19 this turning movement of any enabling lever is communicated 125

through the stud 114 to the bell crank 115 thus turning the bell crank on the stationary shaft 84. There are nine of these bell cranks 115 rotatably mounted on the shaft 84 as shown in Fig. 6, one for each enabling lever and each of these bell cranks is pivotally connected at the lower end to an enabling link 118. The enabling link 118 shown in Figs. 6 and 19 which is operated by the enabling lever 105 is pivotally connected to an arm 119 secured to the rock shaft 120. Thus when the enabling lever 105 is depressed as will be understood from Fig. 6 the bell crank 115 moves the enabling link 118 to turn the rock shaft 120 by means of the arm 119. This turns the arm 121 on the end of the rock shaft 120 so that the lug 122 moves downwardly allowing the pawl 89 to engage over the lever 90 so that upon rotation of the shaft 91 and arm 92 secured thereto, the upper end 93 of the lever by means of the toggle joint turns the lever 94 on the shaft 27 as its pivot to eject a half dollar from the coin stack immediately thereabove as will be understood from Figs. 4, 5 and 6. The rock shaft 124 shown in Fig. 6, is operated by turning the enabling levers 106 or 109 and by an exactly similar mechanism the turning of this shaft 124 prepares the machine to eject a quarter from the coin stack immediately thereover. The rock shaft 125 is operated by turning the enabling lever 107, 110 or 112 and by means of the arm on the end thereof sets the enabling mechanism to eject a dime from the coin stack immediately thereabove. The rock shaft 126 is operated from the enabling lever 108, 111 or 113 and in all other respects is the same as the shaft 125 and upon rotation sets the enabling mechanism to eject a dime from the coin stack immediately thereabove. It will thus be seen that the coin stacks are arranged in one stack containing half dollars, one stack containing quarters, two stacks containing dimes and one stack containing nickels operated from the rock shaft 85. Referring to Fig. 17 it will be noted that the four secondary selector shutters 104 carried by the operating lever 69 control the first four enabling levers 105, 106, 107 and 108. When these four enabling levers are engaged by the said shutters and turned downwardly by depression of the operating lever 69 the four rock shafts 120, 124, 125 and 126 are turned setting the enabling mechanism to discharge a half dollar, a quarter and two dimes. The operating lever 70 by means of the secondary selector shutters 104 carried thereon controls the enabling levers 109, 110 and 111 shown in Figs. 6 and 17. These three levers through the mechanical movements hereinbefore described upon being operated are adapted to turn the rock shafts 124, 125, and 126 setting the enabling mechanism to eject a quarter and two dimes. Referring again to Fig. 17 the operating lever 71 carries two secondary selector shutters

and a dime and depression of the 25-75 operating lever 71 will set the enabling mechanism to eject a dime. This system is carried through the eleven slides until the eleventh slide will set the enabling mechanism to eject a dime only when the dollar operating lever 69 is depressed.

As will be understood from Figs. 2 and 6 all of the parts mounted on the drive shaft 74 are rotatably mounted thereon with the exception of the three arms 127, 128 and 129 shown in Fig. 2. These three arms are secured to rotate with the shaft 74 and support a bail 130. The ends of the five operating levers 69, 70, 71, 72 and 73 extend beneath this bail as shown in Figs. 2, 16 and 24 and sufficient lost motion is provided so that the first downward movement of any of these operating levers sets the enabling mechanism by engaging the different pawls over the different ejecting levers on the right end of the machine. After this first movement of any of the operating levers, the extending end of the lever engages the bail 130 shown in Figs. 2, 16 and 24 and turns the shaft 74 with the respective lever. The shaft 74, as shown in Fig. 6, is provided with a bevel gear 131 on the right hand end thereof meshing with the beveled gear 132 on the shaft 91. With this arrangement the turning of the shaft 74 by any operating lever turns the bevel gear 132 and shaft 91 in a clockwise direction thus turning the arms 92 secured thereto with the shaft 91 and the pawls which are in engagement with the levers 90 turn the levers 90 with the shaft 91. The levers 90 are connected by toggle joints as shown in Figs. 4 and 5 with the five ejection levers immediately thereabove which are pivoted on the shaft 27 and are adapted to eject a half dollar, a quarter, two dimes and a nickel. The portion of the shaft 27 at the left of Fig. 5 is stationary while the ejection levers are rotatably mounted thereon. The portion of the shaft 27 at the right of Fig. 5 is rotatable and is provided with an arm 134 secured thereto as shown in Fig. 5 which is connected by a toggle joint with the arm 135 which is secured to the shaft 91. By this arrangement when the shaft 91 is rotated in a clockwise direction the rotatable portion of the shaft 27 carrying the arms 26, 32 and 35 secured thereto is rotated in a counter-clockwise direction and any of the pawls 25, 31 and 34 which are in engagement with the penny ejector levers 28, 33 and 36 turn these ejector levers with the shaft 27 to eject the selected amount of pennies.

In order to prevent operation until one of the keys on the main keyboard is depressed the release slide 136 shown in Figs. 11, 13 and 23 is provided. This release slide 136 is provided with twenty lugs 137 adapted to be engaged by the bails 47 of the twenty

primary selector shutters. This release slide as shown in Fig. 13 rides on the frame member 138 and a latch 139 is pivotally mounted on each operating lever. This latch 139 engages over the upper edge of the release slide 136 and the release slide is provided with notches 140 normally held out of alignment with the latches 139 as shown in Fig. 11. When any key on the amount due or sale keyboard is depressed the respective primary selector shutter bail 47 moves the release slide 136 to the left so that the notches 140 therein register with the latches 139 and with the notches 141 cut in the frame member 138 so that at this time any of the five operating levers 69, 70, 71, 72 and 73 may be depressed and upon return the latch 139 is turned on its pivot against the tension of the spring 142 and again engages over the upper edge of the release slide 136.

As an example of the operation of the machine we will suppose that a seven cent sale has been made and a dollar tendered by the purchaser. The operator first depresses the Number 7 sale key at the right end of the keyboard shown in Fig. 2 and then depresses the one dollar amount received key 69, shown at the bottom of Fig. 2, causing the machine to discharge a half dollar, a quarter, a dime, a nickel and three pennies a total of 93 cents. The change returned is shown graphically at the right hand end of Fig. 1 in the square in the second vertical column in which 7 cents is the amount due or the amount of the sale. When the 7 key is depressed the bar 3 shown in Figs. 8, 9 and 10 is depressed turning the bell crank 9 and by means of the stud 37 shown in Fig. 8 moving the slides 15 and 17 to the left of Fig. 8. This moves the cams 22 and 24 on the said slides beneath the pawls 25 and 34 shown in Figs. 4 and 5 and engages these pawls over the penny ejector levers 28 and 36, the ejector lever 28 being adapted to eject two pennies from its coin stack and the ejector lever 36 being adapted to eject one penny from its coin stack making a total of three pennies. This same downward movement of the key 7 by means of the shoulder 43 thereon shown in Fig. 7 turns the primary selector shutter 44 on its axis and by means of the bail 47, which engages the lug 97 on the nickel selector slide 49, this slide is moved to the left of Fig. 12 so that the lug 76 is moved off the stud 54. This allows the latch 67 on the dollar operating lever 69 to move into engagement with its companion arm 75. At the same time the movement of the bail 47 as indicated on the 6-10 line at the bottom of Fig. 3 moves the silver selector slide Number 2 to the left. By referring to Fig. 20 the three lugs on the bottom left hand end of slide Number 2 moves the three secondary selector shutters 104 at the left of Fig. 17 into alignment with the three enabling levers 105, 106 and 107.

shown in Figs. 17 and 6. When the dollar operating lever 69 is depressed it depresses the arm 75 and the three enabling levers 105, 106 and 107 thus turning the rock shafts 120, 124, 125 and 85. Rotative movement of these rock shafts allows the pawls normally supported on the arms 121, 144, 145 and 86 on the ends of these rock shafts, as shown in Fig. 6, to engage over the ends of their companion levers as will be understood from Figs. 4 and 5. This completes the primary or enabling movement of the operating lever. Continued downward movement of the dollar operating lever 69 causes the end thereof to engage the bail 130, as will be understood from Fig. 24, thus rotating the shaft 74 and through the gears 131 and 132 shown in Fig. 6, turning the shaft 91 in a clockwise direction. This turns the levers engaged by the pawls at the bottom of Figs. 4 and 5 with the shaft 91 and by means of the toggle joints operates the selected ejector levers to discharge a half dollar, a quarter, a dime and a nickel thus completing the secondary or ejecting movement of the operating lever. As will be understood from Fig. 5 this turning movement of the shaft 91 turns the lever 135 secured thereto and by means of the toggle joint turns the arm 134 secured to the rotatable portion of the shaft 27. This turns the arms 26 and 35 with the shaft 27 and by means of the pawls 25 and 34 turns the ejector levers 28 and 36 to discharge three pennies so that the coins discharged consist of a half dollar, a quarter, a dime, a nickel and three pennies making a total of 93 cents.

From the foregoing description it becomes evident that the device is very efficient in operation, will automatically return the exact change for any transaction, is very easily operated and provides a device which accomplishes the objects described.

Having thus fully described my invention, its utility and mode of operation, what I claim and desire to secure by Letters Patent of the United States is—

1. In an automatic change making machine, a keyboard consisting of a multiplicity of sales keys numbered from 1 to 99 and arranged in five lateral rows so that any key in the lower lateral row must return four pennies in change, any key in the next lateral row must return three pennies in change, any key in the third lateral row must return two pennies in change, any key in the fourth lateral row must return one penny in change and no key in the fifth lateral row returns pennies, a penny selection mechanism individual to each lateral row except the fifth and operated by any key of the respective lateral row, the keys being also arranged on the keyboard in twenty longitudinal rows so that the amount of silver and nickel coins to be returned for any key in its longitudinal row is the same, a nickel and silver selection

mechanism individual to each longitudinal row of keys and operable by depression of any key in its row, a coin ejection mechanism, a series of amounts received levers, means carried by the amounts received levers and controlled by the nickel and silver coin selection mechanisms for enabling the coin ejection mechanism as the amounts received levers are first moved downwardly, and an operating mechanism actuated by the amounts received levers for ejecting the selected coins subsequent to the enabling operation of the amounts received levers.

2. In an automatic change making machine, a keyboard consisting of a series of sales keys arranged in longitudinal rows, each sales key being provided with a stem, a primary selector shutter extending beneath the key stems of each longitudinal row of sales keys and adapted to be turned on its longitudinal axis by depression of any key stem in the respective longitudinal row, a series of silver selector slides provided with lugs engaged by the primary selector shutters, a series of amounts received levers, a series of secondary selector shutters carried by each amount received lever, each silver selector slide being provided with lugs co-acting with the secondary selector shutters, a series of enabling levers with which the secondary selector shutters are adapted to be moved into operative alignment by the lugs on the silver selector slides, a series of rock shafts adapted to be turned by depression of the different enabling levers, an arm on the end of each rock shaft, a coin ejection mechanism, the turning of the said arms and rock shafts enabling the coin ejection mechanism and continued depression of any amount received lever actuating the enabled coin ejection mechanism.

3. In an automatic change making machine, a keyboard consisting of a series of sales keys arranged in longitudinal rows, each sales key being provided with a stem, a primary selector shutter extending beneath the key stems of each longitudinal row of keys and adapted to be turned on its longitudinal axis by depression of any key stem in the respective longitudinal row, a series of silver selector slides and a series of nickel selector slides provided with lugs engaged by the primary selector shutters, a series of amounts received levers, a series of secondary selector shutters carried by each amount received lever, the silver selector slides being provided with lugs co-acting with the secondary selector shutters, a series of enabling levers with which the secondary selector shutters are adapted to be moved into operative alignment by the lugs on the silver selector slides, a latch on each amount received lever adapted to be moved into operative position upon movement of the different nickel selector slides, a coin ejection mechanism

adapted to be enabled by depression of the secondary selector shutters and latches on the amounts received levers, and means for operating the enabled coin ejection mechanism upon continued downward movement of any amount received lever.

4. In an automatic change making machine, a keyboard consisting of a series of sales keys arranged in longitudinal rows, each sales key being provided with a stem, a primary selector shutter extending beneath the key stems of each longitudinal row and adapted to be turned on its longitudinal axis by depression of any key stem in the respective longitudinal row, a series of nickel selector slides provided with lugs engaged by the primary selector shutters, a series of amounts received levers, a latch pivotally mounted on each amount received lever, a series of companion arms adapted to be engaged by the said latches, means on the nickel selector slides normally preventing the latches from engaging the companion arms, movement of the nickel selector slides allowing the selected latches to engage the companion arms, a nickel ejection mechanism enabled by downward movement of any amount received lever whose latch is in engagement with its companion arms, continued downward movement of the respective amount received lever operating the nickel ejection mechanism.

35. In an automatic change making machine, a keyboard consisting of a series of sales keys arranged in longitudinal rows, each sales key being provided with a stem, a primary selector shutter extending beneath the key stems of each longitudinal row of sales keys and adapted to be turned on its longitudinal axis by depression of any key stem in the
40 respective longitudinal row, a series of silver selector slides provided with lugs engaged by the primary selector shutters, a series of amounts received levers, a series of secondary selector shutters carried by each amount received lever, each silver selector slide being provided with lugs co-acting with the secondary selector shutters, a series of enabling levers with which the secondary selector shutters are adapted to be moved into operative alignment by the lugs on the silver selector slides, a coin ejection mechanism adapted to be enabled by depression of the enabling levers, and means for operating the enabled coin ejection mechanism upon continued
45 downward movement of any amount received lever.

18. 6. In an automatic change making machine, a keyboard consisting of a series of sales keys arranged in five lateral rows, each sales key being provided with a stem, a bar extending beneath the stems of each lateral row except one, each bar being adapted to be depressed by any key stem in its lateral row, a bell crank for each bar adapted to be turned by depression of the bar, a stud on each bell crank, a

series of penny selector slides adapted to be operated by movement of the different studs, a penny ejection mechanism adapted to be enabled by operation of the different selector slides, the arrangement being such that depression of one bar enables the coin ejection mechanism by means of the selector slides to return four pennies, depression of another bar enables the coin ejection mechanism to return three pennies, depression of another bar enables the coin ejection mechanism to return two pennies and depression of the remaining bar enables the coin ejection mechanism to return one penny.

7. In an automatic change making machine, a keyboard consisting of a series of sales keys arranged in lateral and longitudinal rows, a penny selection mechanism individual to the lateral rows of sales keys, a nickel and silver selection mechanism individual to the longitudinal rows of sales keys, a coin ejection mechanism, a series of amounts received levers rotatably mounted on a common shaft and adapted to turn the shaft therewith after a predetermined downward movement of any lever, an enabling mechanism adapted to enable the coin ejection mechanism according to the selection mechanism during the predetermined downward movement of any amount received lever, the arrangement being such that rotation of the aforesaid shaft by any amount received lever operates the ejection mechanism to eject the selected coins.

8. In an automatic change making machine, a keyboard consisting of a series of sales keys arranged in lateral rows, each sales key being provided with a stem, a bar extending beneath the stems of each lateral row except one, each bar being adapted to be depressed by any key stem in its lateral row, a bell crank for each bar adapted to be turned by depression of the respective bar, a stud on each bell crank, a series of penny selector slides adapted to be operated by movement of the different studs and a penny ejection mechanism adapted to be enabled by operation of the different selector slides. 100 105 110

9. In an automatic change making machine, a keyboard consisting of a series of sales keys arranged in five lateral rows, a stem to which each sales key is secured, a series of four bars for the first four lateral rows of sales keys, each bar extending beneath the sales key stems of its lateral row, each bar being adapted to be depressed by depression of any sales key in its lateral row, a penny selection mechanism operated by depression of any bar and a coin ejection mechanism enabled by the selection mechanism, the arrangement being such that depression of the different bars enables the coin ejection mechanism to eject one, two, three or four pennies. 115 120 125

10. In an automatic change making machine, a keyboard consisting of a series of sales keys arranged in lateral and longitudinal 130

5 dinal rows, a penny selection mechanism individual to each lateral row except one and operable by any key in the respective lateral row, a nickel and silver selection mechanism individual to each longitudinal row of keys except two and operable by any key in the respective longitudinal row, a coin ejection mechanism, and a series of amounts received levers adapted to be operatively connected with the coin ejection mechanism by the different selection mechanisms and adapted to return the correct change for the amount received for any sale.

10 11. In a machine of the character described, a keyboard consisting of a multiplicity of sales keys arranged in lateral and longitudinal rows, each key in any lateral row except one being adapted to actuate a penny selection mechanism common to all the keys of its row, and each key in any longitudinal row being adapted to actuate a nickel and silver coin selection mechanism common to all the keys of its row, a coin ejection mechanism, and a series of amounts received levers adapted to actuate the cam ejection mechanism.

15 12. In an automatic change making machine, a keyboard consisting of a series of sales keys numbered from 1 to 99 and arranged in five lateral rows so that any key in the lower lateral row must return four pennies in change, any key in the next lateral row must return three pennies in change, any key in the third lateral row must return two pennies in change, any key in the fourth lateral row from the bottom must return one penny in change, and no pennies are returned by any key in the fifth lateral row, a penny selection mechanism individual to each lateral row except the fifth and operable by any key of the respective lateral row, each key on the keyboard except those numbered 91 to 99 being also adapted to operate a nickel and silver selection mechanism.

20 13. In an automatic change making machine, a keyboard consisting of a series of sales keys numbered from 1 to 99 and arranged in five lateral rows and twenty longitudinal rows, a penny selection mechanism individual to each lateral row except one and operable by any key in the respective lateral row, a nickel and silver selection mechanism individual to each longitudinal row of keys and operable by any key in the respective longitudinal row, a coin ejection mechanism and a series of amounts received levers adapted to first enable the coin ejection mechanism according to the selection mechanism and secondly to actuate the ejection mechanism to eject the selected coins.

25 14. In an automatic change making machine, a keyboard consisting of a series of sales keys numbered from 1 to 99 and arranged in five lateral rows and twenty longitudinal rows, a penny selection mechanism

30 individual to each lateral row except one and operable by any key in the respective lateral row to select the same number of pennies, and a nickel and silver selection mechanism individual to each longitudinal row of keys and operable by any key in the respective longitudinal row to return the same amount in nickel and silver coins. 70

35 15. In a machine of the character described, a keyboard consisting of a multiplicity of sales keys arranged in five lateral rows and twenty longitudinal rows, a penny selection mechanism operated by the keys of each lateral row on the keyboard except one, a nickel and silver selection mechanism operated by the keys of each longitudinal row of keys on the keyboard, a series of amounts received levers, a coin ejection mechanism, and means operated by the depression of the amounts received levers for actuating the coin ejection mechanism to discharge the selected coins. 80

40 16. In a machine of the character described, a keyboard consisting of a multiplicity of sales keys arranged in lateral and longitudinal rows, each key in any lateral row except one being adapted to actuate a penny selection mechanism common to all the keys of its row and each key in any longitudinal row being adapted to actuate a nickel and silver coin selection mechanism common to all the keys of its row, a coin ejection mechanism, a series of amounts received levers, and means carried by the amounts received levers for operating the coin ejection mechanism to 95 eject the selected coins. 100

45 17. In an automatic change making machine, a keyboard consisting of a series of sales keys arranged in lateral and longitudinal rows, a penny selection mechanism individual to the lateral rows of keys, a nickel and silver selection mechanism individual to the longitudinal rows of keys, a series of amounts received levers, a common shaft on which the amounts received levers are pivotally mounted, a coin ejection mechanism adapted to be enabled according to the selection mechanism upon the first downward movement of any amount received lever, continued downward movement of any amount received lever subsequent to the enabling movement turning the aforesaid shaft to operate the enabled coin ejection mechanism and eject the selected coins. 110 115

50 18. In a machine of the character described, a keyboard consisting of a multiplicity of sales keys arranged in lateral and longitudinal rows, each key in any lateral row except one being adapted to actuate a penny selection mechanism common to all the keys of its row and each key in any longitudinal row except two being adapted to actuate a nickel and silver coin selection mechanism common to all the keys of its row. 120 125

55 19. In an automatic change making ma-

130

chine, a main shaft, a series of amounts received levers having a primary and secondary movement, the said levers being rotatable on the main shaft during the primary movement, an enabling mechanism actuated by any amount received lever during its primary movement, a coin ejection mechanism with which the enabling mechanism is operatively connected, the secondary movement of any amount received lever turning the main shaft therewith and actuating the enabled coin ejection mechanism.

20. In an automatic change making machine, a main shaft, a series of amounts received levers rotatably mounted on the main shaft, a coin ejection mechanism adapted to be enabled by primary movement of the amounts received levers on the main shaft, the secondary movement of the amounts received levers rotating the main shaft therewith to acutate the enabled coin ejection mechanism.

21. In an automatic change making machine, a selection mechanism, a coin ejection mechanism, an enabling mechanism for the coin ejection mechanism, a main shaft, a series of amounts received levers rotatable on the main shaft and adapted upon primary movement to operate the enabling mechanism according to the selection mechanism and upon secondary movement to rotate the main shaft and actuate the enabled coin ejection mechanism.

22. In an automatic change making machine, a selection mechanism, a coin ejection mechanism, an enabling mechanism for the coin ejection mechanism, and a series of amounts received levers adapted upon primary movement to operatively connect the selection and enabling mechanisms and upon secondary movement to actuate the enabled coin ejection mechanism.

23. In an automatic change making machine, a keyboard consisting of a series of sales keys numbered from 1 to 99 and arranged in five lateral rows and twenty longitudinal rows, a penny selection mechanism individual to each lateral row except one and operable by any key in the respective lateral row, and a nickel and silver selection mechanism individual to each longitudinal row of keys and operable by any key in the respective longitudinal row.

24. In an automatic change making machine, a keyboard consisting of a series of sales keys arranged in lateral and longitudinal rows, a penny selection mechanism individual to the lateral rows of keys and a nickel and silver selection mechanism individual to the longitudinal rows of keys.

In testimony whereof I sign this specification.

EDGAR MAYNARD CAMP.
